UNITED STATES PATENT OFFICE.

HENRIETTE BOURSIER, OF NEW YORK, N. Y.

DOMESTIC HEATER.

1,268,428.

Specification of Letters Patent.

Patented June 4, 1918.

Application filed April 12, 1918. Serial No. 228,111.

To all whom it may concern:

Be it known that I, HENRIETTE BOURSIER, citizen of the Republic of France, residing at New York city, New York, have invented 5 certain new and useful Improvements in Domestic Heaters, of which the following is a specification.

This invention relates to domestic heaters of the type in which the water to be 10 heated is contained in a jacket surrounding the hearth; and it comprises, briefly, an improved heater of the character indicated which will occupy but small space, is simple in its construction and inexpensive to 15 manufacture, and in which wood, coal, sweepings and refuse may be burned as fuel, the water being heated in an extremely short time to a relatively high temperature.

An embodiment of the invention is illustrated in the accompanying drawing, in 20 which Figure 1 is a vertical section of the improved heater, with parts in elevation, and Fig. 2 a horizontal section on line 2—2, Fig. 1.

25 Referring more particularly to said drawing, 1 designates the base, to which the grate or hearth 2 is fixed and on which is mounted the cylindrical water jacket containing the water to be heated. This jacket consists 30 of outer and inner vertical shells 3 and 4, arranged in spaced, concentric relation to each other and closed at their tops by the covers 5 and 6, as shown. The chimney 7 extends through both covers, and the two 35 shells are connected together adjacent their upper ends by the strip 8, which is located in the space between said shells and forms the top of the jacket. Water is supplied to the jacket at the lower portion thereof by 40 way of the inlet pipe 9, and, after having been heated in the manner hereinafter described, leaves the top of the heater through the outlet pipe 10.

Within the interior of the heater is mounted 45 a hollow, sheet metal cone 11, the flat bottom or base of which is disposed above and parallel with the grate 2, and has a diameter somewhat less than that of the inner jacket wall or shell 4, thus providing an annular 50 passage or channel between the base of the cone and the said shell through which the flames and products of combustion of the burning fuel on the grate can pass and completely envelop the cone.

55 The water to be heated is supplied to the cone through an inlet pipe 12, which pro-

jects horizontally into the cone from the jacket and is fastened to the inner shell 4 thereof in any suitable manner. This pipe is located comparatively close to the base 60 of the cone, and has its free end 13 open, so that the water is discharged therethrough toward the opposite wall of the cone, said wall, as well as the axis of the cone, being directed, at an angle to the vertical, toward 65 the shell 4, instead of toward the chimney 7. Adjacent its free end, there opens into said pipe 12 the lower end of a vertical connecting pipe 14, the upper end of which opens into a horizontal outlet pipe 15, the 70 latter projecting outwardly from the upper portion of the cone into the jacket and is likewise fastened to the shell 4. The connecting pipe 14 is formed intermediate its ends with a plurality of superposed pairs of 75 openings 16, which are arranged in staggered relation, as shown, or in some other similar manner, so that they open through the circumferential wall of the pipe in different directions. The upper or outlet pipe 80 15 has its inner end provided with an inlet opening 17 for the water in the cone.

In operation, water enters the bottom of the jacket through the inlet 9, and circulates in the jacket until it reaches the cone inlet 85 pipe 12, whereupon it flows into the cone and, as above stated, is discharged against the inclined wall of the cone and is deflected laterally to either side. Some of the water entering the pipe 12 ascends, however, through 90 the connecting pipe 14, instead of flowing through the outlet end 13, and is discharged into the cone through the openings 16. In consequence, the water, as it rises 95 in the cone, has imparted to it to a greater or less extent, a spiral or whirling motion, due to the jets of water ejected laterally through the openings 16, so that the water is caused to flow through the cone around and against the walls thereof, against which 100 the flames and products of combustion directly contact, as previously explained. The opening 17 in the pipe 15 acts, however, as an inlet for the water, which flows there- 105 through into said pipe and thence into the jacket, the passage of the water through said opening being facilitated, to some extent at least, by the suction or drag created by the water flowing through the connecting pipe 14; the highest pair of openings 16 110 may also, and possibly does, exert a similar action, though the lower pairs obviously act

as ejectors, as explained. The heated water passes from the jacket, by way of the pipe 10, to the point where it is drawn off.

Owing to the fact that the cone is entirely 5 surrounded by the flame and products of combustion, the heating of the water in the cone takes place very rapidly, and the circulation is more intense than that which occurs in the lower portion of the jacket 10 where the water is cooler. Also, since the base of the cone is disposed directly above the grate, a comparatively small quantity only of fuel is needed to effect the heating, and scrap paper, sweepings, and other 15 waste, with the addition of a little wood, may be utilized as fuel, thereby avoiding the danger ordinarily present in oil-burning heaters.

I claim as my invention:

20 A water heater, comprising, in combination, a base; a grate secured thereto; a water jacket mounted on said base and encircling said grate; a water supply pipe opening into the lower portion of the jacket; a discharge 25 pipe for the heated water leading from the top of the jacket; a heating cone disposed within the jacket above the water supply

pipe and having its base directly overhanging the grate and of a diameter which is appreciably less than that of the inner wall 30 of the jacket to provide an annular channel between said inner wall and said base, thereby to enable the flame and products of combustion to completely envelop the cone, said cone having its axis inclined toward said 35 inner shell; inlet and outlet pipes projecting outwardly from the interior of the cone adjacent the base and vertex thereof, respectively, into the interior of said jacket, the inlet pipe having its free end open to 40 permit water to flow therethrough into the cone, and the outlet pipe having an opening in its inner end to admit the water thereinto; and a vertical pipe within the cone connecting said inlet and outlet pipes and 45 through which a portion of the water passing through the inlet pipe is caused to flow, provided with a plurality of ejection openings for delivering jets of water into the 50 interior of the cone to set up a whirling motion of the water in the cone.

In testimony whereof I affix my signature.

HENRIETTE BOURSIER.
